UNITED STATES PATENT OFFICE.

JAMES G. SHAW, OF SAN JOSE, CALIFORNIA.

HEADLIGHT-DIMMER.

1,324,625.

Specification of Letters Patent. Patented Dec. 9, 1919.

Application filed April 22, 1919. Serial No. 291,916.

To all whom it may concern:

Be it known that I, JAMES G. SHAW, a citizen of the United States, and resident of San Jose, in the county of Santa Clara and State of California, have invented certain new and useful Improvements in Headlight-Dimmers, of which the following is a specification.

My invention relates to a means of controlling and dimming the light waves of an artificial light at a point near their source, and particularly to so controlling, confining, directing and dimming the light rays of a headlight for motor vehicles as to more or less completely eliminate the blinding glare to which the occupants of another approaching car, or pedestrians, are subjected.

Further objects of my invention are to provide a device of the character indicated that will be simple in construction and operation, easily manufactured and applied, and capable of adaptation to any form of headlight.

25 In the drawing:—

Figure 1 is a vertical cross-sectional view through the reflector of a headlight fitted with my improved device.

Fig. 2 is a front elevation of the same.

30 Fig. 3 is an enlarged detail section on 3—3 of Fig. 1.

Fig. 4 is a detail illustration of another embodiment of my invention, parts being broken away.

35 In the drawings, 1 indicates a headlight reflector having a true parabolic form such as is in common use on automobiles, 2 referring to the electric light bulb positioned therein and 3 the annular flange formed upon its outer edge.

As illustrated, my device consists of an annular ring 4 having a thin flange 5 adapted to engage flange 3 on reflector 1. Ring 4 has a number of inwardly projecting pins 6 formed thereon and symmetrically arranged as shown, the upper pin 6 on each side being preferably slightly above a horizontal plane passing through bulb 2. Each pair of oppositely positioned pins 6 is connected with a flat metallic strip as 7 curving downwardly at the center and slightly inclined downwardly from the back toward the front. The upper strip 7 is also carried inwardly to a point near the bulb 2 and each lower strip is also carried inwardly toward its central portion in such

a manner that as a whole the strips 7 present a series of successively ascending and retreating forwardly inclined surfaces.

To the upper strip 7 are secured a plurality of other metallic strips 8 having their upper halves substantially concentric with bulb 2, the larger and outer strip 8 being adjacent flange 5 and the other strips 8 successively diminishing in size and retreating toward bulb 2; and all of strips 8 having their broad surfaces substantially parallel with the axis of the reflector 1. In the drawing I have shown the inner edges of strips 7 and 8 so arranged as to not interfere with the light rays from bulb 2 as they travel toward reflector 1 so that most of the light thrown off by bulb 2 toward reflector 1 is received by said reflector and thrown forward through the spaces between the several strips 7 and 8.

I prefer to render the strips 8 and the upper surfaces of strips 7 non-reflecting by a suitable coating of black or dark green light absorbing material and to highly polish the lower surfaces of strips 7. Since the serviceable light from a headlight is practically all reflected light, the bulb 2 itself may be rendered invisible by means of a suitable guard, in the present case in the form of a cone as 9, mounted in the central strip 8.

The result of this construction is that the light rays as 10 may play upon reflector 1 in the usual manner, and be reflected outwardly through the front of the reflector 1 as at 11 almost in their entirety, the obstruction offered by elements 7 and 8 being but slight in comparison with the area of unobstructed surface and the illuminating power of the reflector is but slightly, if any, impaired.

To an observer positioned at a point somewhat above the reflector or to either side of the same, the reflecting surface itself may not be visible. But under the ordinary conditions of an automobile approaching an observer the reflecting surface would be visible until closely approached, and it is during this approaching period that my device functions, perhaps, in its most valuable manner. During this period, the observer may have a practically full and then a gradually decreasing view of the reflecting surface. But the reflecting surface has mirrored in it the darkened surfaces of elements 8, and also to some extent the darkened upper

surfaces of elements 7, and these mirrored images of elements 7 and 8 are reflected back to the observer, the reflected images of the darkened surfaces destroying the glare hereinbefore referred to in so far as the observer is concerned.

The form and position of members 7 are such that they cut off from direct view the lower part of the reflector 1 and they are 10 preferably polished and finished upon their under sides so that no darkened images are formed in the lower portion of the reflector, but the light striking said surfaces is reflected back with but little loss of brilliancy 15 and thence out through the front of the reflector between said members 7.

While good results are secured without the use of cone 9 it is preferred to insert the said cone, with a darkened inner surface, 20 so as to form a darkened image in that portion of the reflector immediately surrounding bulb 2.

While I have herein shown and described one specific form and application of my invention, I do not wish to be confined to the 25 specific construction set forth, but to include all changes in form, construction, arrangement and combination of parts, members and features that may be included within 30 the scope of the appended claims.

I claim:

1. A means for controlling the light from a reflector having a source of light positioned therein, comprising a series of spaced, 35 overlapping elements having their front and rear edges successively retreating from the front of said reflector toward said source of light and having their inner edges spaced a distance from said reflector, a plurality 40 of said elements extending transversely of said reflector below said source of light, each of said last mentioned elements having greater width than thickness, having its ends fixedly mounted adjacent the forward edge 45 of said reflector, its inner edge spaced a distance from said reflector, its outer edge curving inwardly from each end to the center

thereof, its upper and lower surfaces inclined downwardly and forwardly from said source of light.

2. A means for controlling the light from a reflector having the source of light positioned therein, comprising a plurality of spaced elements extending transversely of the reflector and successively ascending and 55 retreating toward said source of light from the bottom edge of said reflector, and a plurality of spaced elements substantially concentric with the axis of the reflector mounted upon the uppermost of said transversely positioned elements and successively 60 descending and retreating toward the source of light therein from the upper and side edges thereof.

3. Means for controlling the light from a 65 reflector having the source of light positioned therein, comprising a plurality of spaced elements extending transversely of the reflector and having their front and rear edges successively ascending and retreating 70 toward the said source of light from the bottom edge of said reflector, and a plurality of spaced elements arranged substantially concentric with the axis of the reflector and above the said transversely positioned elements and having their front and rear edges successively descending and retreating toward the source of light therein 75 from the upper and side edges thereof.

4. Means for controlling the light from a 80 reflector having the source of light positioned therein, comprising a series of spaced, overlapping elements having their front and rear edges successively retreating from the front of said reflector toward said source of 85 light and having their inner edges spaced a distance from said reflector, and a hollow, opaque conical closure concentrically and fixedly mounted with relation to said elements, and positioned between the innermost 90 of said elements with its apex directed outwardly.

Executed this 15th day of April, 1919.
JAMES G. SHAW.
